IMPACT DETONATOR

Leopold S. Serog, Woodside, Long Island, N. Y.

Application April 8, 1941, Serial No. 387,527

2 Claims. (Cl. 102—75)

The present invention relates to a detonator device for projectiles and more specifically pertains to means for causing the detonation of projectiles violently ejected or discharged and adapted to explode upon impact.

An object of the invention resides in providing a detonating mechanism wherein energy is stored during sudden forward movement of the projectile so that the stored energy may be employed for moving a needle of the detonating mechanism to a detonating position when the forward movement of the projectile is suddenly arrested.

Another object of the invention resides in providing a detonator for projectiles including therein means for preventing premature and inadvertent explosion of the projectile.

A more specific object of the invention pertains to the provision of yieldable means in which energy is stored only upon the sudden forward motion of the projectile so that the stored energy will be available for moving the needle into engagement with a percussion cap or an igniter of the projectile when the forward movement of the projectile suddenly stops.

A still further object of the invention includes the provision of an inertia member in a detonating mechanism which is moved rearwardly upon the discharge of the projectile for compressing a spring so that the compressed spring may move a needle of the detonating mechanism into a position to explode the projectile when the projectile strikes some obstacle.

Other features and objects of the invention will be apparent from a consideration of the accompanying drawing and the following description of the invention wherein an exemplary embodiment of the invention is disclosed.

In the drawing:

Fig. 1 is a longitudinal sectional view of a detonating device embodying the invention.

Fig. 2 is a transverse sectional view of the detonator taken on the line II—II of Fig. 1.

Referring to the drawing there is shown at 1 a tubular body member adapted to form the housing or casing for the detonating mechanism. The outer part of the body member 1 is provided with threads 7 for mounting the detonating device in the shell of a projectile such as an artillery projectile adapted to be violently discharged from a gun or a mortar. The forward end of the tubular body member 1 is closed by means of a threaded plug 2. A needle 4 is mounted for sliding movement within the rear portion of the tubular body 1. For this purpose

the casing 1 is provided with a substantially cylindrical opening 15 which terminates in a forwardly arranged annular shoulder 13. The needle 4 is preferably cylindrical-shaped so as to slide within the cylindrical bore 15 in a guided manner. The rear end of the needle 4 is provided with a pointed projection 21 which is adapted to engage a percussion cap or other type of igniting means (not shown) when the needle 4 is released for 10 rearward motion as hereinafter described.

A sleeve 5 is mounted for guided slideable movement within an enlarged bore 16 of the body member 1. The sleeve 5 is provided with a plurality of fingers 10. These fingers are preferably formed from an integral part of the sleeve 5 and are circumferentially spaced as shown in Fig. 2. The fingers 10 terminate to provide hook-shaped ends 12. These hooks or catches 12 are adapted to engage the needle 4 within an annular recess 11 provided in the periphery of the needle 4. The body member 1 is slightly enlarged at 14 forwardly of the annular shoulder 13 so as to accommodate the shank portions of the fingers 10. The needle 4 and the sleeve 5 are 25 prevented from moving rearwardly from the position shown in Fig. 1 by means of the annular shoulder 13. In other words the hook-shaped ends 12 engaging the needle 4 in the annular recess 11 prevent the needle from moving rearwardly and outer portions of the hook-shaped ends 12 engage the annular shoulder 13 so that the needle 4 cannot be moved into a detonating position. Thus the projectile cannot be inadvertently or prematurely exploded.

35 The detonating mechanism includes means for storing sufficient energy for moving the needle 4 to a detonating position. Such means includes an inert or an inertia member 3. The inertia member is mounted adjacent the sleeve 5 and preferably within the forward end thereof. A spring 6 is interposed between the inertia member 3 and the needle 4. Any suitable means may be provided for maintaining the spring 6 in an operable position such as the shoulder 22 on the needle 4 and the annular recess 23 in the inertia member 3. The spring 6 in the position shown in Fig. 1 is not compressed and is thus substantially incapable of exerting any force on the needle 4. When the projectile carrying the detonating mechanism as shown in Fig. 1 is discharged and suddenly moved forward the inertia member 3 moves rearwardly in the sleeve 5 and compresses the spring 6 so as to store energy therein. The sleeve 5 is connected to the inertia member 3 in the rear position thereof by means

of yieldable projections 9 which move radially outward after the inertia member 3 has passed rearwardly beyond the annular shoulder 8 carried by the sleeve 5. Thus the inertia member 3 is retained in a position to maintain the spring 6 in a compressed state and the inertia member is also connected to the sleeve 5. The compression of the spring 6 however cannot move the needle forwardly since the annular shoulder 13 and the hooked ends 12 of the fingers 10 prevent the rearward movement of the needle 4.

During the forward travel of the projectile and the detonating mechanism the velocity of the projectile slowly decreases and the forward speed is reduced. The inertia member 3 and the socket 5 would normally develop a tendency to move forward during the decreased speed of the projectile. A spring 17 is therefore provided between the plug 2 and the forward end of the sleeve 5 which yieldably maintains the socket 5 in the position shown in Fig. 1.

When the projectile strikes an obstacle or is abruptly stopped the inertia member 3 together with the sleeve 5 and the needle 4 moves forwardly. The forward movement of the sleeve 5 pulls the fingers 10 and the hooked ends 12 thereof to a position beyond the forward end of the bore 14. The fingers 10 may thus be biased outwardly into the annular space 18 so as to be disengaged from the annular recess 11. The fingers 10 may be designed to normally move radially outward or the spring 6 acting on the needle 4 may cause the arcuate-shaped hooked ends 12 to move from the annular recess 11. When the needle 4 is released the compressed spring 6 expands and the energy stored therein is sufficient to move the needle 4 rearwardly to a detonating position. Thus the projectile is discharged when the forward motion is abruptly stopped and such abrupt deceleration of the projectile causes the inertia member 3 to move the sleeve 5 so as to disconnect the fingers from the needle 4.

It will be appreciated that the detonating mechanism is so constructed as to eliminate any danger of premature explosion of the projectile since the needle cannot be released for movement to a detonating position until the spring 6 is compressed and the compression of the spring can only be accomplished by sudden forward movement of the projectile such as being discharged from a gun. The projectile likewise cannot be exploded until the shell strikes the objective or some obstacle so as to suddenly stop the forward motion thereof and thus move the inertia member forwardly so as to disconnect the needle 4 for movement to a detonating position.

While the invention has been described with reference to specific structural details it will be appreciated that changes may be made therein by those skilled in the art. Such changes may be made without departing from the spirit and scope of the invention as set forth in the appended claims.

I claim:

1. A detonator for a projectile comprising, a tubular body member, a cap on said body member, a needle slidable in the body member to a rear detonating position, a sleeve slidably mounted in the body member, rearwardly extending fingers carried by said sleeve and terminating in hook-shaped ends, said needle having an annular recess therein for receiving said hook-shaped ends, an annular shoulder carried by said body member engaged by the ends of said fingers and preventing rearward movement of said fingers, an inertia member mounted for sliding movement within said sleeve and adapted to move rearwardly upon discharge of the projectile, a spring between the needle and the inertia member adapted to be compressed by the rearward movement of the inertia member upon sudden forward movement of the projectile, yieldable projections carried by the inertia member for engaging the sleeve in the rearward position of the inertia member, another spring between the sleeve and the cap for normally maintaining the sleeve in a retracted position but adapted to be compressed when the sleeve and the inertia member are moved forwardly upon sudden deceleration of the projectile so that the hooked ends of said fingers are disengaged from said needle and the first mentioned spring then forces the needle rearwardly to a detonating position.
2. A detonating mechanism for a projectile comprising, a body member, a cap for said body member, a needle having an annular recess therein mounted for movement to a rearward detonating position in the body member, a sleeve slidably mounted in the body member, integral fingers extending from the sleeve terminating in hook-shaped ends engaging the needle in said recess, an annular shoulder carried by the body member engaged by the ends of said fingers preventing rearward movement of the fingers and the needle, means carried by the body member retaining the fingers in said recess, an inertia member mounted for movement within said sleeve, an untensioned spring extending between the inertia member and the needle adapted to be tensioned by rearward movement of the inertia member upon sudden forward movement of the body member, yieldable projections carried by the inertia member, an annular shoulder carried by the sleeve adapted to be engaged by said yieldable projections in the rearward position of the inertia member and another spring between the cap and the sleeve maintaining the sleeve in its normal retracted position and adapted to be compressed when the inertia member and the sleeve are moved forwardly upon arrested forward motion of the body member so that the fingers are pulled from the means retaining them in said recess so that the first mentioned spring may force the needle to a detonating position.

LEOPOLD S. SEROG.
